Primary Examiner — Paul D Bohannon*(74) Attorney, Agent, or Firm* — Michael Best & Friedrich LLP(57) **CLAIM**

I claim the ornamental design for a chair, as shown and described.

DESCRIPTION

FIG. 1 is a perspective view of a chair according to the design.

FIG. 2 is a first side view of the chair of FIG. 1.

FIG. 3 is a second side view of the chair of FIG. 1.

FIG. 4 is a front view of the chair of FIG. 1.

FIG. 5 is a rear view of the chair of FIG. 1; and,

FIG. 6 is a top view of the chair of FIG. 1.

The broken lines shown in the drawings illustrate portions of the article that form no part of the claimed design.
